US0D1077728S

(12) **United States Design Patent** (10) **Patent No.:** **US D1,077,728 S**
(45) **Date of Patent:** **** Jun. 3, 2025**

(54) **VAPORIZER BATTERY**

(71) Applicant: **SHENZHEN YOCAN TECHNOLOGY CO., LIMITED,**
Shenzhen (CN)

(72) Inventor: **Zhilong Zhang**, Shenzhen (CN)

(73) Assignee: **SHENZHEN YOCAN TECHNOLOGY CO., LIMITED,**
Shenzhen (CN)

(**) Term: **15 Years**

(21) Appl. No.: **29/896,066**

(22) Filed: **Jun. 28, 2023**

(51) LOC (15) Cl. **13-02**

(52) U.S. Cl.

USPC **D13/103**

(58) **Field of Classification Search**

USPC D13/103, 107, 108, 118, 119; D27/167

(57) **CLAIM**

The ornamental design for a vaporizer battery as shown and described.

DESCRIPTION

FIG. 1 is a front and top perspective view of a vaporizer battery in accordance with a first embodiment showing my new design;

FIG. 2 is a bottom and rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the vaporizer battery in accordance with a second embodiment;

FIG. 10 is a bottom and rear perspective view thereof;

FIG. 11 is a front elevational view thereof;

FIG. 12 is a rear elevational view thereof;

FIG. 13 is a left side elevational view thereof;

FIG. 14 is a right side elevational view thereof;

FIG. 15 is a top plan view thereof; and,

FIG. 16 is a bottom plan view thereof.

The broken lines in the drawings depict portions of the vaporizer battery that form no part of the claimed design.
